RAIL TOOL

E. D. Jones, Grand Junction, Tenn.

Application July 15, 1946, Serial No. 683,631

4 Claims. (Cl. 254—43)

1

This invention relates in general to pushing and pulling tools and more specifically to a tool of this kind which is particularly useful in adjusting adjoining rail ends where necessary such as in aligning the bolt holes in the rails with the holes in the fish plates which are used to couple them together.

The general object of the invention is to provide a tool of the class described which is simple in construction, easy to manufacture, light in weight but having a very high resistance to buckling, easy to operate, and which is rugged, highly efficient and reliable in use.

Another object is to provide an improved rail tool which does not have to be removed from the rails to enable trains to pass. Another object is to provide a rail tool which may be quickly set up and removed from the rails. Yet another and more specific object is to provide a rail tool of the rod and turnbuckle type in which the rods are stiffened laterally to prevent them from buckling when the tool is used for pushing the rails apart.

These and other objects and advantages of the invention will become more apparent from the following detailed description when considered with the accompanying drawings which illustrate a preferred construction of the invention.

In the drawings, Fig. 1 is a side elevation of the tool in place at a rail joint; Fig. 2 is a plan view of the tool in place on the rails; Fig. 3 is a sectional view taken on lines 3—3 of Fig. 2, the tool being shown in end elevation; and Fig. 4 is a perspective view of the rail clamp by which each end of the tool is clamped to the rail.

Referring now to the drawings, the tool comprises a pair of L-shaped rods 10 and 11 threaded on both ends, which are adapted to be placed alongside the abutting rail ends 12, 13 on both sides of the rail joint 14. The shank portions 10a, 11a of these rods are arranged in end-to-end relation and are coupled together by a turnbuckle 15 which is used to exert a pushing or pulling force on the rods that is correspondingly transmitted to the rail ends. The end portions of the turnbuckle terminate in hexagonal nuts 15a for receiving a spanner wrench 16.

The foot portions 10b, 11b of the rods extend under the bed flanges 12a, 13a of the rails between adjacent cross-ties 17 and are arranged to be clamped to these flanges by any suitable clamping device.

In the preferred embodiment of the invention, the clamping device for each rod is comprised of fixed and movable clamping jaws 18, 19, re-

spectively that are holed for assembly on the foot portions 10b, 11b. Jaw 18 which is fixed to the foot portion of the rod at the downwardly turned corner of the L such as by welding at 27, includes an upper jaw plate 18a and a lower hemicylindrical jaw 18b. These jaws form a recess 20 for receiving one side of the bed flange of the rail.

The movable jaw 19 likewise includes an upper jaw plate 19a and parallel spaced lower jaw plates 19b that are disposed transversely and edgewise to jaw plate 18a. These jaws form a recess 20a for receiving the other side of the bed flange of the rail.

As clearly shown in Fig. 2, the bed flanges 12a, 13a of the rail ends 12, 13 fit between the fixed and movable jaws 18, 19 and the jaws are clamped tightly thereto by nut 21 that is threaded onto the end of the foot portion of the rods, a washer 22 being assembled on the rod ahead of the nut if desired. The clamping jaws 18, 19 grip the bed flange of the rail tightly and the novel arrangement of the upper and lower jaw members 18a, 18b and 19a, 19b prevents the jaws from rotating as the clamp is tightened.

When the tool has been clamped to the rail ends, and assuming the ends to be too far apart, the latter may be pulled together, using wrench 16 to rotate the turnbuckle 15 until the bolt holes 13b in rail end 13 come into alignment with the holes 23a in fish plates 23, so that bolts 24 may be thereafter inserted through the fish plates and rail to thereby connect the rail ends 12 and 13 together.

It will be noted from Fig. 1 that when the tool has been applied to the rails, all parts thereof lie below and away from the rail head portions 12c, 13c. Thus the tool has the advantage that it does not have to be removed when a rail joint is being worked on in order to permit a train to pass. Furthermore an additional and even more important advantage inherent in applicant's rail tool is the safety factor since the tool may be left in place without any danger whatsoever of causing a train to be derailed should the workers go off the job and forget to remove the tool.

When the tool is used to force the rail ends apart, a considerable amount of compressional stress is obviously set up in the rods 10 and 11 as the latter are pushed on in opposite directions by the turnbuckle action. These stresses create a tendency in the rods to buckle. To prevent this, the rods are stiffened or reinforced in a lateral direction. In the illustrated embodiment, this lateral stiffness is attained through the use of flat stiffener bars 25 projecting laterally from

each of the rods 10 and 11. One end of each bar is provided with an eye portion 25a by which the bars may be assembled on the rods and adjusted axially therealong. The bars 25 extend beneath the rails to the opposite side thereof and are holed at 25b to receive spikes 26 that are driven into the cross-ties 17.

These stiffener bars add but little to the overall weight of the tool but yet so strengthen its resistance to buckling that the rods 10 and 11 can be made from a substantially smaller diameter stock than would be possible were the lateral stiffener members to be eliminated. The tool thus has a very favorable strength-weight factor which not only reduces its cost but also makes it much easier for workmen to carry on the job.

In conclusion, I wish it to be understood that while I have illustrated and described a preferred embodiment of my improved pushing and pulling tool, various changes in the construction and arrangement of parts may be made without departing from the spirit and scope of the invention as defined in the appended claims.

I claim:

1. In a tool of the class described for use on abutting rail ends, a pair of rods adapted to be placed in end-to-end relation alongside the rail ends, means clamping the remote ends of said rods to the flange portions of their associated rail ends, a turnbuckle connecting adjacent ends of said rods to thereby exert a pushing or pulling force on said rail ends dependent upon the direction of rotation of said turnbuckle, and a transverse bar connected to a medial position on each of said rods, said bars being adapted to be spiked to cross-ties.

2. A tool for use on rail abutting rail ends comprising, a pair of rods arranged to lie in end-to-end relation longitudinally of the rail ends, a turnbuckle connecting adjacent threaded ends of said rods, means for clamping the opposite end of each rod to its associated rail end, and means imparting lateral stiffness to each of said rods intermediate its ends, each said stiffening means comprising a transverse bar adapted to be placed under the rail of a cross-tie, one end of said bar being connected to the associated rod at a medial

position thereof and the other end being holed for spiking to the cross-tie.

3. In a tool for use in pushing or pulling abutting rail ends, a pair of L shaped rods adapted to be placed in end-to-end relation longitudinally of the rail ends, the foot portion of each said rod extending under its associated rail, a pair of jaws on the foot portion of each rod, one jaw of each pair being fixed to the foot portion and the other movable thereon for gripping the rail flange between them, means clamping the jaws of each pair tightly to the rail flange, a turnbuckle connecting adjacent ends of said rods to push or pull on the rods, and means imparting lateral stiffness to each rod at a point intermediate its foot portion and said turnbuckle, each said stiffening means comprising a transverse bar connected at one end to the associated rod and adapted to be spiked at the other end to a cross-tie.

4. In a tool for use in pushing or pulling abutting rail ends, a pair of L-shaped rods adapted to be placed in end-to-end relation longitudinally of the rail ends, the foot portion of each said rod extending under its associated rail, a pair of jaws on the foot portion of each rod, one jaw of each pair being fixed to the foot portion and the other movable thereon for gripping the rail flange between them, means clamping the jaws of each pair tightly to the rail flange, a turnbuckle connecting adjacent ends of said rods to push or pull on the rods, and a transverse bar associated with each of said rods for imparting lateral stiffness thereto, each one of said bars being provided with an eye for mounting the same on the rod and the other end being holed for spiking to a cross-tie.
